UNITED STATES PATENT OFFICE.

DELBERT M. WESTCOTT, OF SKAGWAY, DISTRICT OF ALASKA.

DESIGN FOR A SOUVENIR-BADGE.

No. 39,726.

Specification for Design.

Patented Dec. 29, 1908.

Application filed June 25, 1908. Serial No. 440,407. Term of patent 3½ years.

To all whom it may concern:

Be it known that I, DELBERT M. WESTCOTT, a citizen of the United States, residing at Skagway, District of Alaska, have invented a new, original, and ornamental Design for Souvenir-Badges, of which the following is a specification, reference being had to the accompanying drawing, forming a part thereof.

The figure is a view in front elevation of a souvenir badge, showing my new design.

I claim:

The ornamental design for a souvenir badge, as shown.

DELBERT M. WESTCOTT.

Witnesses:

PHIL. ABRAHAMS,
WM. BRITT.
